UNITED STATES PATENT OFFICE.

ADÉLARD J. GOBEIL, OF DULUTH, MINNESOTA, ASSIGNOR OF ONE-HALF TO
MARY M. DEETZ AND EDWARD W. DEETZ, COPARTNERS AS DEETZ &
CO., OF DULUTH, MINNESOTA.

WINDOW FRAME AND SASH.

No. 845,298.

Specification of Letters Patent.

Patented Feb. 26, 1907.

Application filed September 29, 1905. Serial No. 280,569.

To all whom it may concern:

Be it known that I, ADÉLARD J. GOBEIL, a citizen of the United States, residing at Duluth, in the county of St. Louis and State of Minnesota, have invented certain new and useful improvements in Window Frames and Sashes; and I do hereby declare the following to be a full, clear, and exact description of the invention, such as will enable others skilled in the art to which it appertains to make and use the same.

My invention relates to window-sash, and has for its object the provision of a strong, light, and easily-constructed sash of bent sheet metal.

It has for a further object the provision of a removable and adjustable glass-retaining strip adapted for use with such a sash as part thereof, and which may be adjusted for use with various thicknesses of glass.

With these and other objects in view it consists of the constructions, combinations, and arrangements of parts hereinafter described and claimed.

In the accompanying drawings, Figure 1 is a perspective view, partly broken away, of the upper and one side rail and mullion-strip or an upper sash included in my said invention. Fig. 2 is a horizontal section of a mullion-strip included in my said invention. Fig. 3 is a vertical section, partly broken away, of the lower rail of an upper sash, and of the upper and lower rails of a lower sash, all included in my said invention, omitting the mullion-strip. Fig. 4 is a horizontal section of my improved side frame for a window, showing side rails of my window-sashes positioned therein.

In the drawings, 1 is the cover of the top rail of the upper sash, which is bent, as at 1^a, 1^b, and 1^c, to form a groove or channel for engaging a hook-flange 2^d, formed on the body portion of said upper rail. The upper face of the upper rail is also preferably bent, as at 1^d, but may, if desired, be constructed flush across the top, as shown by the dotted line. The body portion of the upper rail is bent to form side walls 2, a weather-shoulder 2^a, a floor 2^b, and a strip-receiving groove 2^c. As will be observed, the bottom rail of the lower sash is constructed approximately the same as the top rail of the upper sash, and the parts are therefore designated by similar

reference characters. The lower rail of the upper sash is in most respects constructed the same as the lower rail of the lower sash, and similar reference characters are used to designate similar parts; but in constructing said lower rail of the upper sash I preferably bend the body portion to additionally form thereon the shoulder 2^e. The cover of the bottom rail of the upper sash is also preferably modified as to its bends, having, preferably, only the bends 1^a, while the hook-flanges of the lower rail of the upper sash are also preferably modified to include the bend 2^f. The coengaging bends of or between the body portion of the various rails and their respective covers may, however, be modified in various ways, readily occurring to any mechanic skilled in the art and in view of the forms I have shown, and I do not, therefore, desire to be limited to the exact forms of bends of these coengaging parts, as shown.

The upper rail of the lower sash is constructed approximately the same as the lower rail thereof, except that the cover is preferably integral with said body portion and the coengaging bends and hook-flanges 2^d are omitted, the cover being bent over from one side wall and continued, as at 2^g, to bend over and engage a lip 2^h, bent outwardly from the opposite side wall and overlapping the shoulder 2^e on the lower rail of the upper sash. The side rails of both sashes are constructed substantially the same as the upper rail of the upper sash.

The upper and lower and side rails of each sash, respectively, are preferably united at their ends and connected together in any convenient manner, as by leaving projecting ends on the covers of the horizontal rails, which projecting ends are bent over the ends of the covers of the vertical rails and are riveted thereto, as clearly shown in Fig. 1.

3 represents glass, and 4 represents patty.

5 is a removable glass-retaining strip having the tongue 5^a and the shoulder 5^b. By altering the angle of the bends between the body portion 5 and the tongue 5^a and shoulder 5^b said strip may be adjusted to retain various thicknesses of glass. The end of the shoulder 5^b may within the scope of my invention be modified in various ways, as by being turned outwardly from the rail instead of inwardly toward it, or otherwise, which

modifications will readily occur to any one interested in making them and will require no further description.

The mullion-strip of my said sash is a modified form of the sash-rail, said mullion comprising the cover 6 and hook-flanges 6^a, the body portion having opposite weather-shoulders 7 and 7^a, parallel floors 7^b and 7^c, parallel groove-forming bends 7^d and 7^e, a central spacing portion 7^f, and hook-flanges 7^g. Said mullion is adapted to receive into the grooves formed by its bends 7^d and 7^e the tongues of corresponding glass-retaining strips similar to such strips already described herein, and said shoulders are, as in the side and upper and lower rails of each of said sashes, adapted to form back-stops for such glass-putty or other suitable sealing material being preferably interposed between said glass and back-stops.

While I have shown the coengaging or interlocking bends of the covers and body portions bent sharply or at right angles, it will be obvious without further description that such bends may be rolled or otherwise modified, as suitable and desired. It will also be obvious without further description that any of the walls of said rails or mullion may be further bent to form ornamental contours without departing from my said invention.

I have found in practice that a convenient way of constructing the sashes is to make the body portions of the rails and mullions separately, and then slip their respective covers on longitudinally, and then secure the horizontal rails to the vertical rails, as hereinbefore indicated.

My improved metallic side frame for windows comprises a sheet-metal front portion 8, bent in one or more places to form recesses, as at 8^a, adapted to receive the tongues 9 of sash-retaining strips, which strips are further provided with angular extensions 9^a or 9^b and 9^c, adapted to overlap the flange of the contiguous sash, and not only to form guide and retaining walls for the sash, but to obstruct the passage of air between the sash and the window-frame, rendering the window at such place wind and weather proof. The space A may be occupied in part by the counterbalance-weight of the sash and the space B by the weight-suspending cords. (Not shown.) Said side frame also includes, preferably, a back or cover portion 8^b, secured to said front portion by any suitable engaging bends, as 9^c.

In operation the horizontal rails of the respective sashes being secured together and the mullion or mullions (if any used) being secured in position by any convenient means, preferably by riveting them to the upper and lower rails before the covers of said rails are put on, putty is spread upon or against the shoulders 2^a, and the glass or glasses are laid upon or against the putty. The tongues 5^a

of the glass-retaining strips 5 are then slipped into the tongue-receiving grooves of the rails and mullion, respectively, and the shoulders 5^b will then bear against the glass and hold it in position. The upper horizontal glass-retaining strips may be supported upon the upper ends of the vertical glass-retaining strips. If desired, the tongues of the glass-retaining strips may be secured in the rail-grooves by a loose angular pin 2¹ or by any other convenient means. Where only one sheet of glass is used in each sash, the mullion may be omitted.

My window-sashes, as above described, are particularly desirable on account of their substantially fireproof character.

Having now described my invention, what I claim, and desire to secure by Letters Patent, is—

1. A window-sash having grooves formed in its horizontal and vertical rails, and removable and adjustable glass-retaining strips provided with tongue portions adapted to project into said grooves and shoulder portions adapted to bear against the glass. 90

2. A window-sash constructed of bent sheet metal, each rail of said sash being contoured to form a weather-shoulder and a tongue-receiving groove, and removable glass-retaining strips each having a tongue 95 adapted to project into the groove of the corresponding rail and a shoulder adapted to bear against the glass.

3. A window-sash including a rail having a body portion constructed of sheet metal bent to form a weather-shoulder, a supporting-floor, a tongue-receiving groove, side walls and cover-engaging flanges; and a cover constructed of sheet metal bent at its edges to form hook-flanges adapted to engage the hook-flanges of said body portion. 100

4. In a window-sash, a mullion having weather-shoulders formed thereon and having tongue-receiving grooves formed therein, and removable glass-retaining strips each having a tongue adapted to project into the corresponding said groove, and each having a shoulder adapted to bear against the glass. 110

5. In a window-sash, a mullion constructed of sheet metal and comprising a body portion bent to form cover-attaching flanges, weather-shoulders, tongue-engaging grooves and a spacing portion; a cover portion bent to form body-attaching flanges; and removable glass-retaining strips having shoulder portions adapted to bear against the correspondingly-adjacent glasses, and having tongue portions adapted to project into the corresponding said grooves. 115

6. In a window-sash the combination of side and upper and lower rails constructed of sheet metal bent to form weather-glass-retaining shoulders and tongue-receiving grooves; a plurality of removable glass-retaining strips constructed of sheet metal and 130

each bent to form a tongue adapted to engage a corresponding one of said grooves and each embodying a shoulder adapted to bear against said glass; a mullion comprising a body portion constructed of sheet metal bent to form opposite weather-shoulders and parallel tongue-receiving grooves; and plurality of glass-retaining strips each constructed of sheet metal bent to form a tongue adapted to

project into the corresponding groove of said mullion and to form a shoulder adapted to bear against the contiguous glass.

In testimony whereof I hereunto affix my signature in presence of two witnesses.

ADELARD J. GOBEIL.
